UNITED STATES PATENT OFFICE.

JOHN O. WAGNER, OF CHICAGO, ILLINOIS.

ADJUSTABLE SCREEN HANGER FOR WINDOWS.

Application filed April 9, 1923. Serial No. 630,851.

To all whom it may concern:

Be it known that I, JOHN O. WAGNER, a citizen of the United States, and a resident of the city of Chicago, in the county 5 of Cook and State of Illinois, have invented certain new and useful Improvements in an Adjustable Screen Hanger for Windows; and I do hereby declare that the following is a full, clear, and exact description 10 of the same, reference being had to the accompanying drawings, and to the numerals of reference marked thereon, which form a part of this specification.

This invention relates to an adjustable 15 screen hanger for windows.

In the past, it has been more or less difficult to hang the screens upon the windows from the outside on account of the danger involved. It was likewise difficult to un- 20 hinge them, and in cases where the window frame has sagged or is not of true form, the standard screen for such size of window would not closely fit the frame.

It is an object of this invention to over- 25 come these difficulties by providing a screen hinged to an adjustable hanger which may be secured to either the top or a lateral side of the window frame, and that is capable of sufficient adjustment to com- 30 pensate for limited irregularities in the size of the window frames; the hinges that connect the screen and hinge being deflected inwardly and connected by removable pintles or the like which may be inserted 35 or removed by a person standing within the window or adjacent room.

With these and other objects in view which will become more apparent in the following description and disclosures, this 40 invention comprises the novel mechanism and combinations hereinafter described and more particularly pointed out and defined in the appended claims.

In the accompanying drawings which 45 illustrate a preferred embodiment of this invention and in which similar reference numerals refer to similar features in the different views:

Figure 1 is an outer elevational view of 50 a screen supported according to my invention.

Figure 2 is an enlarged and broken section upon the line 2—2 of Figure 1.

Figure 3 is an enlarged outer elevational 55 view of the hanger and the upper frame member of the screen.

Figure 4 is a fragmentary enlarged elevational view of the interior of the screen and hanger with the window frame shown in section. 60

Figure 5 is an enlarged sectional view upon the line 5—5 of Figure 3.

Figure 6 is a fragmentary elevational view of a modified form of hanger.

Figure 7 is an enlarged fragmentary sec- 65 tional view embodying the modified hanger.

Figure 8 is a view similar to Figure 7 showing a further modified form of sup- 70 porting the hanger.

In referring now to the drawings, there 75 is illustrated a window frame upon the outer surface of which the screen is hinged so that it can swing outwardly upon its hinge. While the screen may be hinged to either the top or a lateral side of the window frame, I preferably hinged it to the top rail as shown in the drawings.

According to this invention, an adjustable hanger 1 in the form of a narrow metal strip or the like is adjustably secured to 80 the outer surface of the top rail 2 so that it is frictionally retained and may be manually adjusted. One way of attaching this hanger is illustrated in Figure 3 and consists in providing a plurality of slots 3 85 therein for receiving the attaching screws 4 which screw into the rail 2 and frictionally bind the hanger against the rail. At suitable points the hanger is provided with cut-out portions 5 as shown in Figure 6 and just above these cut-out portions, hinge members 6 are secured. These hinge members 6 are deflected inwardly through the cut-out portions and the inner ends thereof are in the form of eyes. 90

Mating hinge members 7 are secured to the top member of the screen frame, and these hinge members are bent or deflected inwardly over the top of the screen; their inner ends being provided with spaced eyes 100 between which the eyes on the hinge members 5 fit so that hinge pintles 8 may be inserted through said eyes for hinging the screen to the hanger. It should be observed that these inwardly directed hinge 105 members make it possible for a person to readily hang the screens or remove the same when standing in the room, by merely inserting or removing the hinge pintles 8.

In case the window frame has sagged so 110 that the screen will not exactly fit the same, the hanger 1 may be adjusted by pulling

it downwardly sufficiently. If only one side of the frame has sagged, only one end of the hanger 1 is pulled downwardly, whereby the same assumes an inclined or oblique position.

If the irregularities of the size of window cannot be taken care of by the adjustment of the hanger as shown in Figure 3, the latter may be suspended by a pair of short straps 9 as illustrated in Figure 6. In this case, the short straps are provided with a pair of slots, and screws extend through these slots for respectively attaching the straps to the window frame and hanger 1^a. The screws frictionally bind the straps 9 to the window frame so that the same may be vertically adjusted and frictionally bind the hinges to the straps so that the hanger may be vertically adjusted with respect to the straps whereby a double adjustment is provided.

Instead of attaching the hanger as shown in Figure 3 or as shown in Figures 6 and 7, it may be attached to the rail by the angle clips 10 shown in Figure 8, whereby one flange of the angle clips is secured to the bottom of the rail 2, and the other flange is adjustably connected to the hanger 1^b by a slot and screw connection. In this construction, the angle clips may readily be attached by a person within the room, overcoming the difficulty encountered by attaching the same upon the outer surface of the rail.

After the hanger has been once attached to the window frame by any of the illustrated methods, it is a very simple matter for a person standing within the room to hang the screen to the hanger and properly adjust the same to compensate for any irregularities in the size of the window. To do this, it is only necessary to register the hinge members on the screen with those on the hanger and insert the hinge pintles, and then adjust the hanger if necessary. The screens can also readily be unhung or removed by a person standing within the room by withdrawing the hinge pintles.

On account of the adjustment provided by the hanger, it is possible to construct

screens varying $\frac{1}{2}$ " or $\frac{1}{4}$ " in sizes which may be kept in stock so that special screens need not be constructed for distorted or sagged window frames.

I am aware that numerous details of construction may be varied through a wide range without departing from the principles of this invention, and I therefore do not purpose limiting the patent granted, otherwise than necessitated by the prior art.

I claim as my invention:

1. The combination with a window frame, of a member adjustably secured to the outer surface thereof and having hinge members extending inwardly, a screen having inwardly directed hinge members adapted for registering with the first hinge members, and removable pintles for connecting said hinge members.

2. The combination with a window frame, a strip adjustably secured thereto, and a screen hinged to said adjustable strip.

3. The combination of a window frame, of means for adjustably supporting a screen hinge member thereto, a screen, and detachable hinge connection between said screen and hinge member operable from within the window frame.

4. In a structure of the class described, a screen hanger comprising a strip having slots for adjustably receiving attaching means, and spaced cut-out portions, hinge members secured to one side of said strip and extending through said cut-out portions to the opposite side thereof in combination with a screen having inwardly deflected hinge members, and means for releasably connecting said hinge members.

5. The combination with a window frame, of a screen, means for adjustably hinging said screen to said frame, and means operable from within the window frame for unhinging said screen.

In testimony whereof I have hereunto subscribed my name in the presence of two subscribing witnesses.

JOHN O. WAGNER.
